SWEEPING INDICATOR FOR DUST SUCTION
PIPES

Daniel Benson Replogle, Berkeley, Calif.; Bank of America National Trust and Savings Association, Carl S. Replogle, Harold E. Queen, and Laurie H. Bullock, executors of said Daniel Benson Replogle, deceased, assignors to The Ohio Citizens Trust Company, Toledo, Ohio, a corporation of Ohio, as trustee

Application January 7, 1942, Serial No. 425,927

8 Claims. (Cl. 302—65)

The invention relates to dust indicators for suction cleaning systems of the general type set forth in my copending application Ser. No. 411,931, filed September 22, 1941, now Patent No. 2,293,920, dated August 25, 1942.

As in my aforesaid patent, the primary object of the present invention is to provide an improved visible indicator whereby the quantity and quality of dust being drawn through the system will be readily apparent to the operator of the cleaner.

In common with the disclosure of my patent No. 2,293,920 the present device comprises an indicator interposed in the cleaning system at some point between a suction nozzle and a source of suction, and includes a diaphragm element or deflector ring adapted to be positioned within the indicator casing diagonally with reference to the inlet and outlet of the indicator. The diaphragm is provided with a central opening to allow passage of air through an exit toward the source of suction, and the opening may be, and preferably is, protected by a screen which is adapted to retain large objects as, for example, objects of value, such as jewelry and the like, which may have been accidentally drawn into the system.

According to the present invention, ready access to the interior of the indicator may be had by means of a removable cover.

Another feature of the invention resides in the provision of a frame for the screen permitting ready removal thereof and replacement by a screen of different mesh, if desired, or permitting the operation of the indicator without any screen.

Another feature of the invention is the provision of improved means whereby the screen may be freed of accumulated dirt without reversing the direction in which the air is whirling about the indicator, this being accomplished, according to a preferred embodiment of the invention, by shifting the diaphragm from one diagonal position with reference to the inlet and outlet openings to the opposite diagonal position with reference thereto. A thumb or finger piece readily accessible to the hand of the operator may be employed for shifting the diaphragm in one direction and a suitable spring may be employed for returning the diaphragm to its initial position when the finger piece is released.

The invention will be more readily understood by reference to the accompanying drawing, which is intended as illustrative only rather than as limiting the invention to the particular details set forth.

In the drawing:

Fig. 1 is a left-side assembly view of the indicator;

Fig. 2 is a top plan view of the same, with the cover shown slightly separated;

Fig. 3 is a bottom view of the same;

Fig. 4 is an elevation showing the diaphragm and supporting and operating means therefor, the screen having been removed from the diaphragm;

Fig. 5 is an edge view of the diaphragm;

Figs. 6 and 7 are, respectively, an elevation and an edge view of the removable screen, and

Fig. 8 is a diagrammatic view illustrating the indicator in use.

15 Referring first to Fig. 8, A denotes the indicator, which is adapted to be held in the hand of the operator in the upright position as shown. The inlet pipe of the indicator is adapted to be connected to a tubular section B of the suction cleaning system, which section leads from a suction nozzle (not shown). The outlet portion of the indicator is connected to a tubular section C of the suction cleaning system which communicates with a suitable source of suction (not shown). One 20 or both sides of the indicator may be formed of transparent material, or the entire indicator may be transparent, to permit the operator to observe the incoming dust.

The indicator is provided with a deflecting ring 30 or diaphragm D, which is adapted to cause whirling movement of the air entering through the inlet, and this diaphragm is set diagonally across the indicator casing between the inlet and outlet openings.

35 As more clearly shown in Figs. 2 and 3, the indicator includes a cylindrical body portion 10, which may be of metal or plastic synthetic material. The body or casing 10 is provided with a short inlet pipe 11 and a short outlet pipe 12. The casing may be formed of two initially identical stampings 13 and 14, each of which includes one-half of the inlet and outlet pipes. The halves are joined together along a vertical center line 15 and are welded or otherwise secured together to include the diaphragm D, which is rotatably mounted on a central vertical axis XY. One of the halves 13 of the casing may be formed with an integral rounded end wall 16, while the other half is provided with an open face adapted to be closed 40 by a cover 17 of transparent material which may be slipped over the flange 18 of the member 14, or, if desired, both faces of the body or casing may be punched out and provided with transparent covers, but greater strength is secured by 45 retaining the end wall 16 integral with the casing,

as illustrated. On the other hand, greater visibility may be obtained by making the entire body 10 of transparent material.

The diaphragm D comprises a deflector ring 20 of any suitable material, as metal, cardboard, or plastic material, and may be either opaque or transparent. The deflector ring is adapted to be mounted for limited rotation about a vertical axis, and for this purpose is provided with a supporting and actuating member or yoke, generally designated by the reference numeral 21, which yoke includes upper and lower vertical shaft portions 22 and 23 the ends of which serve as bearings, a circular portion 24 intermediate the vertical portions 22 and 23 which circular portion bounds the central opening 25 of the diaphragm and provides a seat for a screen member 40, shown in Figs. 6 and 7. The yoke also includes a crank or handle portion 26 extending outside of the casing of the indicator, which handle may be supported and guided in a U-shaped stirrup 27 secured to the base of the casing at a position slightly removed from the lower bearing member 22. The stirrup 27 serves as a combined support, stop and guide for the handle or finger piece 26. The diaphragm D is normally held in the diagonal position with reference to the inlet 11 and outlet 12, shown in Figs. 2 and 3, by means of a spring 28a carried by the handle 26 and having a portion bearing against the interior of the stirrup 27, as best shown in Fig. 3. The diaphragm may be shifted to the opposite diagonal position by manual operation of the handle to permit the air to clean the diaphragm and screen of accumulated dust.

The supporting and operating yoke 21 may be formed of a pair of relatively stiff, yet still resilient, wires 28, 29 of semi-circular cross-section, which wires are welded together at the pivot points 30 and 31 of the yoke and at the handle or crank portion 26, but intermediate the pivot points 30 and 31 the wires 28 and 29 extend over opposite faces of the ring 20, which is yieldingly embraced between them. The diaphragm or ring may be slid into position within the yoke or may be removed therefrom by manual operation, but when mounted in the yoke the diaphragm will be frictionally engaged by the opposite wires 28 and 29.

The screen member 40 includes a rim portion 41 and is adapted to be removably and resiliently mounted in the circular portion 24 of the yoke 21. The screen is accessible from the open side of the indicator casing when the transparent slip-cover 17 is removed.

The operation of the improved indicator will be apparent from the foregoing description. The assembled indicator shown in Fig. 1 is adapted to be included between a pair of adjacent tubular members B and C of a suction cleaning system as illustrated in Fig. 8, the member B fitting the inlet pipe 11 and the member C fitting the outlet pipe 12. The indicator is adapted to be readily applied to or removed from the system when desired. Dust-laden air drawn in through the inlet is given a whirling movement by the deflector ring 20, which extends diagonally between the inlet and outlet, and such air eventually passes through the screen 40 to the outlet, the screen serving to collect any large solid articles. If dust tends to accumulate on one face of the diaphragm and screen, this may be remedied by moving the finger piece 26 with the fingers of the same hand which grips the indicator, as illustrated in Fig. 8, after which the finger piece will

be released to allow the diaphragm to assume its normal position. During the cleaning operation, the amount of dust passing through the system will be readily visible through the transparent cover 17 so that the operator will know how much cleaning is being done. If the transparent cover becomes dirty, it may be readily removed and the interior cleaned. When the cover 17 is removed, the screen 40 is accessible and may be removed for cleaning or other purposes and may be replaced by another screen of different mesh, if desired, or the screen may be omitted entirely.

The invention has been described in detail for the purpose of illustration, but it will be obvious that numerous modifications and variations may be resorted to without departing from the spirit of the invention.

What I claim is:

1. In a dust indicator for a suction cleaning system, wherein the indicator is adapted to be interposed between adjacent tubular elements of the system, said indicator comprising a globular casing member having an inlet and an outlet opening and including a transparent window portion, and means for deflecting air entering said casing against said window, said means comprising an imperforate deflecting annular ring element permanently mounted within said casing and adapted to be positioned diagonally to the inlet and outlet openings; the improvement wherein the ring element is provided with a central annular seat for a removable screen element, and the casing is provided with a removable cover facing the deflecting ring and permitting access to the interior of the casing for removal or replacement of the screen element.

2. In a dust indicator for a suction cleaning system, wherein the indicator is adapted to be interposed between adjacent tubular elements of the system, said indicator comprising a globular casing member having an inlet and an outlet opening and including a transparent window portion, and means for deflecting air entering said casing against said window, said means comprising an imperforate deflecting annular ring element permanently mounted within said casing and adapted to be positioned diagonally to the inlet and outlet openings; the improvement wherein the ring element is provided with a central annular seat for a removable screen element, and the casing is provided with a removable cover facing the deflecting ring and permitting access to the interior of the casing for removal or replacement of the screen element, said deflecting ring element being shiftable to permit accumulated dust to be removed from one side by the incoming air.

3. In a dust indicator for a suction cleaning system, wherein the indicator is adapted to be interposed between adjacent tubular elements of the system, said indicator comprising a globular casing member having an inlet and an outlet opening and including a transparent window portion, and means for deflecting air entering said casing against said window, said means comprising an imperforate deflecting annular ring element permanently mounted within said casing and adapted to be positioned diagonally to the inlet and outlet openings; the improvement wherein the ring element is provided with a central annular seat for a removable screen element, and the casing is provided with a removable cover facing the deflecting ring and permitting access to the interior of the casing for removal or replacement of the screen element, said deflecting

ring element being carried by a yoke pivoted in the wall of the casing member.

4. In a dust indicator for a suction cleaning system, wherein the indicator is adapted to be interposed between adjacent tubular elements of the system, said indicator comprising a globular casing member having an inlet and an outlet opening and including a transparent window portion, and means for deflecting air entering said casing against said window, said means comprising an imperforate deflecting ring element permanently mounted within said casing and adapted to be positioned diagonally to the inlet and outlet openings; the improvement wherein the ring element is provided with a central seat for a removable screen element, and the casing is provided with a removable cover permitting access to the interior of the casing for removal or replacement of the screen element, said deflecting ring element being carried by a yoke pivoted in the wall of the casing member, said yoke having an external handle, and spring means engaging said handle for normally holding the ring element in its initial position.

5. In a dust indicator for a suction cleaning system, wherein the indicator is adapted to be interposed between adjacent tubular elements of the system, said indicator comprising a globular casing member having an inlet and an outlet opening and including a transparent window portion, and means for deflecting air entering said casing against said window, said means comprising an imperforate deflecting ring element permanently mounted within said casing and adapted to be positioned diagonally to the inlet and outlet openings; the improvement wherein the ring element is provided with a central seat for a removable screen element, and the casing is provided with a removable cover permitting access to the interior of the casing for removal or replacement of the screen element, said deflecting ring element being carried by a yoke pivoted in the wall of the casing member, said yoke having an external handle, and a guide means for limiting the movement of said handle.

6. In a dust indicator for a suction cleaning system, wherein the indicator is adapted to be interposed between adjacent tubular elements of the system, said indicator comprising a globular casing member having an inlet and an outlet opening and including a transparent window portion, and means for deflecting air entering said casing against said window, said means comprising an imperforate deflecting ring element permanently mounted within said casing and adapted to be positioned diagonally to the inlet and outlet openings; the improvement wherein the ring element is provided with a central seat for a removable screen element, and the casing is provided with a removable cover permitting access

to the interior of the casing for removal or replacement of the screen element, said deflecting ring element being carried by a yoke pivoted in the wall of the casing member, said yoke having an external handle, and guide means for limiting the movement of the handle, said guide means comprising a U-shaped stirrup mounted on the exterior of said casing member, through which stirrup the handle passes.

10 7. In a dust indicator for a suction cleaning system, wherein the indicator is adapted to be interposed between adjacent tubular elements of the system, said indicator comprising a globular casing member having an inlet and an outlet opening and including a transparent window portion, and means for deflecting air entering said casing against said window, said means comprising an imperforate deflecting ring element permanently mounted within said casing and adapted to be positioned diagonally to the inlet and outlet openings; the improvement wherein the ring element is provided with a central seat for a removable screen element, and the casing is provided with a removable cover permitting access to the interior of the casing for removal or replacement of the screen element, said deflecting ring element being carried by a yoke pivoted in the wall of the casing member, said yoke having an external handle, and guide means for limiting the movement of the handle, said guide means comprising a U-shaped stirrup mounted on the exterior of said casing member, through which stirrup the handle passes.

20 25 30 35 40 45 50 55 60

8. In a dust indicator for suction cleaning systems, wherein the indicator is adapted to be interposed between adjacent tubular elements of the system between the suction nozzle and a source of suction and adapted to be held by the hand of the cleaner operator, said indicator including a globular casing member having a transparent window portion and means within the casing for deflecting entering air against the window, said deflecting means comprising a ring permanently mounted for rotation about a central axis within the chamber, the improvement wherein actuating means for said ring are provided permitting rotation of said ring about its axis by the fingers of an operator at the same time that the indicator is grasped by the same hand of the operator, said actuating means including a handle member rigidly connected to the ring member and extending a substantial distance along the exterior of the casing, said ring being carried by a yoke pivoted in the outer wall of the casing, said handle member being formed integral with said yoke.

DANIEL BENSON REPLOGLE.
